US0D1038929S

(12) **United States Design Patent** (10) **Patent No.:** **US D1,038,929 S**
(45) **Date of Patent:** **** Aug. 13, 2024**

(54) **LAPTOP COMPUTER**

(71) Applicant: **LG ELECTRONICS INC.**, Seoul (KR)
(72) Inventors: **Kyongtae Han**, Seoul (KR); **Kyeal Seo**, Seoul (KR); **Heechang Lee**, Seoul (KR); **Yongho Lee**, Seoul (KR); **Jihoon Shin**, Seoul (KR); **Minji Son**, Seoul (KR); **Junghyun Min**, Seoul (KR)

(73) Assignee: **LG ELECTRONICS INC.**, Seoul (KR)

(**) Term: **15 Years**

(21) Appl. No.: **35/517,213**

(22) Filed: **May 16, 2022**

(80) **Hague Agreement Data**

Int. Filing Date: **May 16, 2022**

Int. Reg. No.: **DM/223281**

Int. Reg. Date: **May 16, 2022**

Int. Reg. Pub. Date: **May 19, 2023**

(30) **Foreign Application Priority Data**

Dec. 14, 2021 (KR) 30-2021-0060335

(51) **LOC (14) Cl.** **14-02**

(52) **U.S. Cl.**

USPC **D14/315**; D14/327

(58) **Field of Classification Search**

USPC D14/315-327, 341-346, 345-346; D21/324, 329-330, 332, 515; D18/1-2, D18/4.1-4.6, 12.2-12.3

(57) **CLAIM**

The ornamental design for a laptop computer, as shown and described.

DESCRIPTION

1. Laptop computer

1.1 : Perspective

1.2 : Front

1.3 : Back

1.4 : Left

1.5 : Right

1.6 : Top

1.7 : Bottom

1.9 : Perspective

1.10 : Front

1.11 : Back

1.12 : Left

1.13 : Right

1.14 : Top

1.15 : Bottom

1.17 : Perspective

1.18 : Front

1.19 : Back

(Continued)

1.20 : Left
1.21 : Right
1.22 : Top
1.23 : Bottom
1.25 : Perspective
1.26 : Front
1.27 : Back
1.28 : Left
1.29 : Right
1.30 : Top

Reproductions 1.1 to 1.7 show the claimed design in the first position, reproductions 1.9 to 1.15 show the claimed design in the second position, reproductions 1.17 to 1.23 show the claimed design in the third position, and reproductions 1.25 to 1.31 show the claimed design in the fourth position; the broken lines depict portion of the article that from no part of the claimed design.

1 Claim, 28 Drawing Sheets

(58) **Field of Classification Search**

See application file for complete search history.
